INVENTOR

Alfred C. Redden

BY

G. Wright Arnold

ATTORNEY

UNITED STATES PATENT OFFICE.

ALFRED C. REDDEN, OF SEATTLE, WASHINGTON.

CALK.

Application filed January 19, 1920. Serial No. 352,436.

To all whom it may concern:

Be it known, that I, ALFRED C. REDDEN, a citizen of the United States, residing at Seattle, in the county of King and State of Washington, have invented a certain new and useful Improvement in Calks, of which the following is a specification.

My invention relates to the art of calks or the like.

10 As heretofore designed, calks have been objectionable in that they would pull out altogether when the leather became softened by water, or in coming in contact with hard surfaces would be distorted in the shoe sole so as to protrude at an angle other than that desired. Moreover such calks are uncomfortable to the feet as no provision is made to distribute their upward thrust when caused to strike hard surfaces.

20 Finally, a very serious objection to calks in shoes and boots as heretofore provided obtains in that calks become rusty readily owing to the exposure of the sole to water. This rust on the calk which is in contact with the leather is injurious, rust being a well known disintegrating agent as respects leather, and operates to weaken the supporting leather about the calk so as to interfere with the proper functioning of the calks.

30 The objects of my invention are: to provide a calk that will obviate these objections; and that will be held firmly in the shoe sole and will maintain its upright position; further, it is a primary object of my invention to provide a calk of such form that only such portions of the supporting leather are put under compression as are unexposed and protected. A primary object is to prevent injury to the leather arising

40 from the rusting of the calks, and thus to avoid weakening the supporting leather about the calk so that its proper functioning is preserved. Also, I purpose providing a calk with a boss disposed to utilize the greatest leverage possible which will serve to reinforce the parts maintaining the upright position of the calk, and at the same time be of such small size as to not cause discomfort to the foot by its upward thrust, since it is my purpose to provide a calk that will cause the upward pressure to be distributed so that the foot is not injured by the upward thrust of the calks when striking against a hard surface, thereby making it possible to make a calked shoe smooth inside. Providing a shoe with calks after

said shoe is manufactured renders the portion next to the foot uneven not only by distorting the sole as a whole but by causing the leather to rise above each calk.

60 The above mentioned general objects of my invention together with others inherent in the same are attained by the mechanism illustrated in the following drawings, the same being merely a preferred exemplary form of embodiment of my invention, throughout which drawings like reference numerals indicate like parts:

Figure 1 shows the sole of a shoe or boot provided with calks embodying my invention;

70 Figure 2 is a view in cross section on line 2, 2 of Fig. 1;

Figure 3 is a view in elevation of a preferred form of calk embodying my invention;

75 Figure 4 is a modified form of calk embodying my invention without a boss;

Figure 5 is also a modified form of the same with a flat head; and

80 Figure 6 is a modified form of the same with a flat head without a boss.

A shank 7 of a calk embodying my invention is provided with a point 8 with side walls 9 and with a broad head or cap 10. Axially disposed with respect to said shank is the boss 11 in the center of said head or cap 10. In the shoe or boot outsole or layer 12 holes 13 are made. Above this outsole or layer 12, is the middle sole or layer 14.

85 In the preferred form of embodiment the head 10 is formed with sloping or convex shoulders 15. In the modified forms, shown in Figs. 5 and 6, the head 10 is formed with a flat surface 16.

90 In manufacturing, an outsole layer 12 of leather or like material is provided with the calk holes 13 in any arrangement desired. Calks embodying my invention are then inserted in the prepared holes, and such outsole is then sewed or otherwise secured, as the bottom layer to the middle sole or upper layers so as to form a unitary shoe or boot sole.

95 In practice, it is manifest that the sides 9 of the shank 7 afford a long bearing surface against which the walls of the prepared holes 13 in the outsole 12 of the shoe sole can bear effectively in maintaining the calk in its upright position, said outsole 12 leaving 100 the point part 8 free to grip a surface to prevent slipping. In the preferred form

these sides 9 are parallel. The head 10 serves to keep the calk from slipping out thru the hole 13 as well as distributing any upward thrust over a considerable portion 45 of the shoe sole.

Moreover, such head reinforces the walls 10 of the hole 13 in maintaining the calk in upright position. The head manifestly forms a compression of the leather fibers about 15 said head whereby the head is partly able to maintain the calk in an upright position. The compressed fibers are thus within the shoe sole and are not exposed to the wear and strains to which the outside surfaces 20 are subject. Thus the objectionable effect of the shrinking of the leather upon drying and its loosening after becoming wet is eliminated. The convex cap or head also is 25 advantageous in affording a tapered edge so that sharp edges which would be subject to cutting the leather are avoidable but also such tapering edge makes it possible for the sole to embrace the calk without 30 raising an objectionable small convex surface above each calk. The boss 11 pierces the slipsole or inner layer 14 of the shoe sole and thereby utilizes the greatest possible leverage (the walls of the hole 13 functioning as a fulcrum) in cooperating in 35 maintaining the said calk in an upright position.

The middle sole 14 is preferably soaked 35 and specially prepared in leather preserving and rust resisting oil. The calks with their 40 broad heads serve to press out this oil. In this wise, the middle sole functions as an oil reservoir and prevents the calks from becoming rusty. In turn, this prevents the portion of the sole engaging the calk from 45 becoming disintegrated and weakened, so that the strength of said leather is preserved and the calk may therefore be relied upon to function properly.

Moreover, it should be noted that the 45 holes in the outersole are made of such size with respect to the size of the shank of the calk that that part of the sole about the hole is not distorted and put under compression strains—the holding of the calk being performed by its head. The boss assists in 50 holding the calk in an upright position. Furthermore, it will be observed that this method of embracing the calk, i. e., with holes of such size as to avoid compression of the leather and the axial position of the 55 boss, provides for a certain amount of yielding or movement on the part of the calk so that it is the better able to sustain distorting effects without being dislodged from its proper position permanently. 60

In the modified forms, the head 10 would less effectively attain the results of the preferred form but would manifestly approximate the various functions, either all or in part, of the preferred form. 65

Obviously, changes may be made in the forms, dimensions, and arrangement of the parts of my invention, without departing from the principle thereof, the above setting forth only a preferred form of embodiment. 70

I claim—

A shoe embodying an oil soaked middle sole, an outer sole having holes punched therein, and a one piece calk disposed in 75 said holes, said calk having a shank with parallel sides, said holes being of a size as compared to the size of said shank as to not distort and put the surrounding leather under compression, and a head relatively much wider than the diameter of its shank, 80 said head being disposed between said outer sole and said middle sole.

In witness whereof, I hereunto subscribe my name this 6th day of January, A. D., 1920.

ALFRED C. REDDEN.
